POCKETED BALL GAME

Theodore B. Stillman, Brooklyn, N. Y.

Application January 16, 1946, Serial No. 641,526

2 Claims. (Cl. 273—125)

1

This invention relates to amusement apparatus in general, and more particularly to an improved game apparatus characterized by a plurality of pockets to intercept a missile such as a ball or the like.

Among the objects of the present invention, it is aimed to provide an improved game apparatus, including an indicator board having a plurality of counting signals, a platform having a plurality of pockets to intercept a missile, such as a ball, some of the pockets cooperating with said board to register gains and other pockets cooperating with said board to register losses.

It is still another object of the present invention to provide an improved game apparatus including an indicator board having a plurality of indicators to register the progress of the player, a platform having a plurality of pockets with electric switches to intercept a missile, such as a ball, to actuate the switch associated with the pocket which intercepted the ball, electric conductors connecting the poles of each switch with one or more of said indicators either to excite an indicator or to disconnect or extinguish one or more indicators according to the pocket which intercepted the ball thereby to register gains when exciting indicators, or to register losses when disconnecting or extinguishing indicators.

These and other features, capabilities and advantages of the invention will appear from the subjoined detail description of one specific embodiment of the invention illustrated in the accompanying drawings, in which

Fig. 1 is a perspective of one of a plurality of apparatus made according to the present invention.

Fig. 2 is a section on the line 2—2 of Fig. 1.

Figs. 3, 4 and 5 are parts of one and the same wiring diagram schematically showing the electrical connections of the apparatus, the dash and dot line 1—1 at the bottom of Fig. 3 coinciding with the dash and dot line 2—2 at the top of Fig. 4, and the dash and dot line 3—3 at the bottom of Fig. 4 coinciding with the dash and dot line 4—4 at the top of Fig. 5.

In the embodiment shown, see Fig. 1, there is illustrated one of the units 1 of a plurality of similar units according to convention having a trough 2 mounted on suitable supports 3. In the trough 2 there is provided a platform 4 spaced at its front end 5 from the front wall 6 of the trough. Near the rear end of the platform 4, there are provided a plurality of interceptors such as the pockets or openings 7, in the present instance twenty-five in number, arranged in five rows of five to

2

a row, and so aligned in accordance with the conventional Bingo board.

Immediately in front of the pockets 7 there is provided an inclined guide 8 to enable a ball or missile rolled or projected on the platform 4 in front of the guide 8 and toward the pockets 7 to roll over the guide 8 and toward the pockets 7. Adjacent to the ends of the guide 8, there are provided the two elongated openings 9 and 10 to receive the ball should it have missed entirely any one of the pockets 7, the platform 4 being inclined downwardly in a forward direction so that the ball will normally roll forward toward the openings 9 and 10 after its trajectory momentum has been spent or after it has struck the rear end wall 11 and started on its return forward movement toward the guide 8. The guide 8 will intercept the ball at the end of its return movement and due to the inclined faces 12 and 13 of the guide 8 direct or guide the ball toward the openings 9 and 10. Below the platform 4, there is provided an inclined wall 14 having a mouth 15. The upper face of the floorboard 16 is also inclined downwardly toward the front end so that the ball, after dropping through a pocket 7, 9 or 10 and onto the floorboard 16, will roll toward the inclined wall 14, and in turn then toward the mouth 15. The balls, such as the ball 17, in diameter are just smaller than the mouth 15 to clear the same, but wide enough to actuate the arm 18 pivotally mounted at 19, controlling the double throw microswitch 20. The microswitch 20 will be energized whenever the arm 18 is engaged by a ball 17 after having been intercepted either by a pocket 7, 9 or 10.

On the lower face of the platform 4 adjacent to each of the openings 7, there is provided a microswitch 21 with its spring pressed projection 22 extending into the path of movement of a ball intercepted by a pocket 7, so that the ball 40 will engage the projection 22 thereby to actuate the microswitch 21.

One of the games that can be played with apparatus made according to the present invention would call for a single ball 17 to each player. In such case, the player would continue to throw the ball 17 until either he or a competing player completed the winning count. The winning count would call for illuminating each of the lamps 23, 24, 25, 26 and 27 which are mounted in the housing 28 in alignment with the translucent spots 29 in the panel 30. The spots 29 cooperating with the lamps 23 to 27, inclusive, thus constitute one display area.

Furthermore, according to the present invention, if the winning player should complete the

winning count within five throws of the ball 17, he would thereby not only illuminate the lamps 23, 24, 25, 26 and 27 in alinement with the translucent spots 29, but also the first five lamps 31, 32, 33, 34 and 35 in alinement with the first five translucent spots 36 in the panel 30 beginning from the left. The first objective of the winner, therefore, is to complete the winning count within the five throws of the ball 17, at which time the lamp 37 in alinement with the translucent spot 38 in the panel 30 will not be illuminated, but the unit 1 of the winning player will remain illuminated while the illumination of all of the other units, such as those connected to the conductors 39 and 40, will be extinguished.

If, however, the winning player required six or more throws, then the double throw microswitch 20, as hereinafter set forth, will cause not only the lamps 31 to 35, inclusive, to be illuminated, but also the sixth lamp 37 in alinement with the translucent spot 38. The translucent spots 36 and 38 and the lamps 31 to 35, inclusive, and 37 thus constitute another display area.

The lamps 23 to 27, inclusive, will be illuminated whenever the ball passes into pockets associated with such lamps. With the exception of the lamp 23, which is associated with pocket 41 alone, each of the remaining lamps 24 to 27, inclusive, is associated with more than one pocket, the lamp 24 being associated with the two pockets 42; the lamp 25 being associated with the four pockets 43; the lamp 26 with the six pockets 44; and the lamp 27 with the ten pockets 45. The two remaining pockets 46 are associated with the lamp 27 of the pockets 45. According to the present game, when the microswitch 21 of either of the pockets 46, 46, is actuated by a ball being intercepted by either of these pockets, then the lamp 27 will be extinguished. Not only the lamp 27 will be extinguished when a ball is intercepted by either of the pockets 46, but in addition, any and all of the lamps 47 associated with the pockets 45 will be extinguished. The lamps 47 are disposed behind translucent spots 48 in the panel 30 in alinement with lamps corresponding in position to the position of the pockets 45 in the platform 4. Each of the lamps 47 will correspond to one of the pockets 45 and be illuminated as its corresponding pocket 45 intercepts a ball. It is conceivable that all of the pockets 45 may intercept the ball, and consequently all of the lamps 47 may finally be illuminated.

In the panel 30, the middle row of lamps which includes two end lamps corresponding to the two end pockets 42 of the platform 4, and a lamp in alinement with the centrally disposed translucent spot 48 corresponding to the pocket 41 of the platform 4 has, in addition, two blank spots or opaque spots 49, 49 with no lamps behind them corresponding in position to the position of the pockets 46 on the platform 4. In other words, only twenty-three of the pockets in the platform 4 have corresponding lamps in the housing 28, the two pockets 46 not having corresponding lamps in the housing 28, and ten of the lamps, to wit, the lamps 47 corresponding to the ten pockets 45, are only conditionally illuminated when a pocket 45 intercepts a ball, the condition being that before the end of the game, the player does not cause the ball 17 to drop into a pocket 46. In such latter case, then all of the previously illuminated lamps 47, illuminated as a result of the

pocket or pockets 45 having intercepted the ball 17, will be extinguished and remain extinguished until in the subsequent playing of the game if it endures beyond such play, the player of a particular unit again causes a ball to drop into a pocket 45. The translucent spots 48 and opaque spots 49 thus cooperate with the lamps 47 to constitute still another display area.

To take advantage of the wide spread knowledge of the terms used in the game of baseball and the great interest in the game of baseball by the American public, the different groups of pockets in the platform 4 are arbitrarily denominated by terms familiar to the baseball public. Furthermore, in view of the different values to certain of these baseball terms, either due to the difficulty or rarity of the achievement denominated by such term, or due to the hazard accompanying the achievement, there is only one pocket, to wit, the pocket 41, which is designated the home run pocket; there are two pockets, to wit, the pockets 42 which are designated the triple hit pockets; four pockets, to wit, the pockets 43 which are designated the double or two base hit pockets; six pockets, to wit, the pockets 44 which are designated the single base hit pockets; and ten pockets, to wit, the pockets 45 which are designated the walk or base on balls pockets. The two pockets 46 are designated the strike out pockets.

Furthermore, the lamp 23 in alinement with the translucent spot 29 in the panel 30 over the initial "H" at the right hand end of the row of translucent spots 29 will be illuminated whenever the home run pocket 41 intercepts the ball 17. At the same time, the lamp 50 in the housing 28 in alinement with the translucent spot 48 between the two blank or opaque spots 49 will also be illuminated. In turn when a ball is intercepted by a pocket 42, not only will the lamp 24 in alinement with the translucent spot 29 above the letter "T" be illuminated, but also one of the lamps 51 in the housing 28 in alinement with the translucent spot 48 corresponding in position on the panel 30 to the position of the pocket 42 which intercepted the ball.

Furthermore, when a ball is intercepted by one of the four pockets 43, not only will the lamp 25 in alinement with the translucent spot 29 above the letter "D" be illuminated, but also the lamp 52 in alinement with the translucent spots 48 corresponding in position on the panel 30 to the position of the pocket 43 in the platform 4.

Furthermore, whenever a ball is intercepted by a pocket 44, not only will the lamp 26 in alinement with the translucent spot 29 above the letter "S" be illuminated, but also the lamp 53 in alinement with the translucent spot 48 corresponding in position on the panel 30 to the position of the pocket 44 which intercepted the ball. Whenever any of the lamps 50, 51, 52 or 53 is illuminated as a result of a corresponding pocket having intercepted the ball 17, such lamp will remain illuminated until the end of the game and not be temporary or in any way conditional upon a subsequent play. The only lamps which are conditional upon a subsequent play are the lamps 27 and 47 as already explained. Finally, however, whenever a ball is intercepted by a pocket 45, not only will the lamp 27 in alinement with the translucent spot 29 above the letter "W" be illuminated, but one of the lamps 47 in alinement with the translucent spot 48, corresponding in position on the panel 30 to the position of the

pocket 45 which intercepted the ball will be illuminated, with this exception, however, as already stated, that the illumination of the lamps 27 and 47 is conditional upon a subsequent play, that is, will be extinguished when the ball in a subsequent play is intercepted by either of the pockets 46, 46.

The first object of the play is, as aforesaid, to cause the ball 17 to be intercepted in five successive throws of the missile by the pocket 41 and one of the pockets of each of the groups 42, 43, 44 and 45, as a result of which each of the lamps 23, 24, 25, 26 and 27 in alinement with the spots 29 in the panel 30 will be illuminated. The second objective of the player is to have pockets intercept the ball so that these five lamps, to wit, 23, 24, 25, 26 and 27 will be illuminated before any of the other players of the game causes such lamps to be illuminated, even though the number of throws by the player may exceed five. In case, however, that the player requires more than five throws, then not only the lamps 31, 32, 33, 34 and 35, in alinement with the first five translucent spots 36 in the panel 30, will be illuminated, but also the lamp 37 in alinement with the sixth translucent spot 36 in the panel 30, indicating to the other players that the player has not achieved his first objective but has achieved his second objective.

In addition to the aforesaid lamps, each unit 1, and preferably on the top of the housing 28, is provided with a lamp 54. This lamp 54, and all of the lamps 54 of the units 1 which enter the play, will be illuminated at the beginning of the play and may for convenience be called the "machine ready for play" lamp. As will herein-after be described, any of the units 1 may conveniently be eliminated from the play before any particular game starts, in which case not only the lamp 54 will remain extinguished, but none of the other lamps in the housing 28 will function during the playing of this particular game.

For a particular game, as many as twenty-five units 1 may be connected to be played together. The wiring diagram contained in Figs. 3, 4 and 5 schematically showing the electric circuit used will now be described.

It is, of course, to be understood that Figs. 3, 4 and 5 are all parts of one and the same diagram, the wiring diagram being divided into these three parts for convenience of illustration only.

A manually actuated fused entrance switch 55 controls the entire circuit being connected to the two main leads 56 and 57. The two main leads 56 and 57 may have connected thereto two conductors 58 and 59, respectively, connected to general illumination equipment to be on at all times when the entrance switch 55 is closed. The conductor 56 in turn is also connected to one of the main conductors 60 of the first unit which will be described in detail, and the lead 57 connected to the other main conductor 61 of the first unit. The main leads 56 and 57 will also be connected to similar main conductors of all of the other units of the machines that are intended to be connected for play in one game, the lead 56 being connected to the main conductor 39 and the lead 57 being connected to the main conductor 40, the conductors 39 and 40 being typical of one or more additional units and connected to circuits that are mere duplicates of the circuit of the first unit which will now be described in detail.

The first unit having the conductors 60 and 61 is provided with a switch symbolized as 62 at the

entrance of the same to permit eliminating the first unit if desired. This switch is also provided with a circuit breaker 63 operatively associated with the switch 62 to open the switch 62 in case of a short circuit or the like due to an over-load.

When all players are in position adjacent to their game apparatus such as the unit 1, the person in charge of the game, such as a master of ceremonies, will press the starting pushbutton 64 into closed position to establish the current to the several units whose switches 62 have been previously closed. By closing the pushbutton 64, which opens as soon as released, a circuit is established from the main lead 51, through conductor 66, starting switch 64, normally closed stop switch 125, conductor 69, relay 72, conductor 70 to main lead 56. When the relay 72 is thus energized one of its switches 65 is closed thereby providing a holding-in circuit after the switch 64 is released. With the closing of switch 64 followed by the closing of switch 65, a circuit is also established through the normally closed stop pushbutton switch 125, the normally closed relay operated switches 80, 81 and 82, relay 71 and conductor 70 to the main lead 56. When the circuit is so established through the conductors 68 and 69 the two relays 71 and 72, respectively, will be energized, the holding-in switch 65 maintaining the relays 71 and 72 energized after the pushbutton 64 is released. The relay 71 when so energized closes the contacts 73 and 74 in the main leads 56 and 57 to the several machines. With the closing of these contacts, the "machine ready for play" lamp 54 will be illuminated at each machine in which the switch 62 has been closed as a signal for the players of such machines or game apparatus to start the game. The relay 72 will also close the contacts 75 and 76 in an auxiliary power line to the machines which is kept open at each machine by contacts 77 and 78 of a relay 79 duplicated in each machine. In series with the main power line relay 71 there are the normally closed contacts 80, 81 and 82. In the present instance, only three contacts 80, 81 and 82 are illustrated to indicate that three machines are hooked up in the present circuit. However, when more machines are hooked up there will be a closed contact such as the contact 80 for each machine, the closed contact 80 in the present instance symbolizing the closed contact for the first unit. The closed contact 80 is provided for the relay 83.

When the switch 62 is closed and momentary contact made by the pushbutton 64 as aforesaid, the circuit to the lamp 54 will be established from the lead 56 to the conductor 60, the conductors 84 and 85 and from the lamp 54 by way of the conductors 86 and 87 to the conductor 61 and return lead 57.

As aforesaid, there is only one home run pocket, the pocket 41. When the ball 17 is intercepted by this pocket 41 it will momentarily close the microswitch 21 associated with the pocket 41, energizing its relay 410, in turn closing three contacts, the holding-in contact 88 across the microswitch 21, the contact 89 closing the circuits to the lamps 50 and 23 in alinement with translucent spots 48 and 29, respectively, in the panel 30, and also the contact 290, see Fig. 5, to the relay 79.

When the ball 17 is intercepted by one of the two triple pockets 42, 42, it will momentarily close the microswitch 21 associated with the pocket 42, energizing the relay 420, associated

with such pocket 42; thereby closing four contacts, either the contact 90 or the contact 91 constituting a holding-in contact across the microswitch 21 which has been tripped, a second contact 92 or 93 lighting up the lamp 51 corresponding in position to the pocket 42 which has intercepted the ball, a third contact 94 or 95 in a parallel circuit to the lamp 24 to light up the same, and a fourth contact 96 or 97, see Fig. 5, to the relay 79.

When the ball 17 is intercepted by one of the four double pockets 43, the microswitch 21 engaged will energize the associated relay 430 which will close four contacts, a holding-in contact 98, 99, 100 or 101 constituting a holding-in contact across the microswitch engaged, a second contact 102, 103, 104 or 105 to light up the lamp 52 in the housing 28 corresponding in position to the pocket 43 which has intercepted the ball, a third contact 106, 107, 108 or 109 to the lamp 25, and a fourth contact 110, 111, 112 or 113 corresponding to the pocket 43 to the relay 79.

In turn, if the ball is intercepted by one of the six single pockets 44, see Fig. 4, the microswitch 21 of the pocket engaged will energize its associated relay 440 in turn to close one of the contacts 114 constituting a holding-in contact for the microswitch engaged, a second contact 115 to light the lamp 53 corresponding in position to the pocket 44 which has intercepted the ball, a third contact 116 for the lamp 26, and a fourth contact 117 for the relay 79.

When the ball 17 intercepts one of the ten walk pockets 45, the microswitch 21 engaged will energize the associated relay 450 in this case to close three contacts, to wit, the holding-in contact 118 for the microswitch 21 engaged, a second contact 119 to illuminate the lamp 47 corresponding in position to the pocket 45 which has intercepted the ball, and a third contact 120 to light lamp 27 and close part of the circuit to the relay 79.

In the case of the circuits for the walk relays 450, it will be noted that the conductor 61 is connected by the conductor 121 having two normally closed contacts 122 and 123 to the common conductor 124 which through the microswitch 21 or holding-in contact 118 is connected by a conductor 162 to the relay 450 which in turn is connected to the conductor 60. The normally closed contacts 122, 123, if momentarily opened, as now to be explained, will open the circuit or circuits to the relays 450, in turn to open any previously closed contact 118, 119, and 120.

The means whereby the normally closed contacts 122 or 123 may be opened will now be described. These contacts will be momentarily opened when the ball 17 is intercepted by either of the strike out pockets 46, 46. When the ball 17 is intercepted by either of the strike out pockets 46, see Fig. 5, the microswitch 21 engaged will momentarily energize the relay 460 corresponding to the pocket 46 which has intercepted the ball. At this time no lamps corresponding to the pockets 46 will be illuminated. On the contrary, the relay 460 corresponding to the pocket which has received the ball will open either the contact 122 or 123. There is no holding-in contact for the microswitch 21 of either of the relays 460 and consequently as soon as the ball passes the microswitch 21, the circuit to the relay 460 will be interrupted in turn again to allow the contact 122 or 123 to be closed. This momentary opening of either the contact 122 or 123, however, as aforesaid will interrupt the circuit or circuits to the relays 450.

of the walk pockets 45 and thereby open any and all of the contacts 118, 119 and 120 previously closed. The reclosing, however, of the strike out contacts 122 or 123 when their function is completed will enable the re-energizing of the walk relays 450 whenever the ball 17 thereafter is intercepted by a walk pocket 45.

As aforesaid, when one or more of each group of relays 410, 420, 430, 440 and 450 are energized, 10 the parallel series circuit energizes the relay 79 in turn to close its contacts. Two of the contacts closed by the relay 79 are the contacts 77 and 78 in the auxiliary supply line to the machine and the third contact closed by the relay 79 will be the contact 324 to the relay 83, which relay 83 when energized will open switch 80 to de-energize the relay 74, thereby interrupting the main power supply line through switches 73 and 74 to all of the machines, extinguishing the lamps and de- 20 energizing all of the relays in all of the machines except the winning machine which obtains its power from the auxiliary supply lines 180 and 190 through which a circuit was established by closing the contacts 71 and 78 by the relay 79 by way of 25 the main lead 57, conductor 66, contact 76, conductor 180, and contact 77 to conductor 61 and by way of the main lead 56, conductor 10, contact 75, conductor 183, and contact 78 to conductor 60.

To de-energize the winning machine the person 30 conducting the game will now push or actuate the normally closed pushbutton 125 on the main control panel. Thereupon subsequent closing of the start pushbutton 64 will start a new game.

The control means for illuminating the lamps 35 31 to 35, inclusive, and 37, will now be described. By reference to Figs. 2 and 5 it will appear that whenever the ball 17 is returned to the player it will actuate the switch arm 18 to trip the double-throw microswitch 20. Reference will now be had more particularly to Fig. 5. Before the first ball is returned, that is, before it engages the arm 18 to trip the microswitch 20, the arm 18 will be in engagement with the contact 126. However, the circuit through relay 127 is not completed until the first ball passes switch 20 for the first count to illuminate lamp 31. When the first ball passes switch 20, arm 18 is swung to contact 140 creating a circuit from conductor 61 through the normally closed relay operated switch 170, arm 18, contact 140, through relay 141 to conductor 60. Relay 141 has six normally open contacts 142, 143, 144, 145, 146 and 147. Contact 142 causes relay 134 to be energized as well as lamp 31, said relay having three contacts, 148 to hold in its circuit, and contacts 150 and 172 which will now remain closed; the contact 172 completing a circuit for relay 127 when arm 18 returns to its biased position against contact 126. Relay 127 has six normally open contacts 128, 129, 130, 131, 132 and 133. With the energization of the relay 134 and the closing of contact 128, relay 149 becomes energized and its holding contact 156 will retain it in circuit and its second contact 157 will continue closed.

With the rolling of the next ball, the switch arm 18 will again energize relay 141 closing its contacts of which contact 143 will complete a circuit to relay 135 to close contact 129 and the second count lamp 32. Relay 135 actuates its holding-in contact 158 and also contact 151 so when arm 18 returns to re-energize relay 127, a circuit will be completed to relay 163 closing its holding-in contact and contact 168, in the circuit of number three count relay 136 and lamp 33 to close contact 130; preparing this circuit for the next or third ball to be rolled.

In like manner, as successively rolled balls actuate switch arm 18 to energize first relay 141 and then relay 127, the remaining count relays 137, 138 and 139 and their respective lamps 34, 35 and 37 will be brought into the closed circuit after the closing of contacts 131, 132 and 133, respectively. In other words, movement of arm 18 to energize relay 141 successively lights the lamps and the return of arm 18 re-energizing relay 127 prepares the circuit for the next lamp. When the last count relay 139 is energized, its second contact 155 closes the circuit of relay 171 which is maintained closed by its holding contact 267, while its other contact 170 is broken to make inoperative switch 18 as further balls are rolled. Breaking of the main supply circuit by either the completion of the game by a winning board or by the operator through stop switch 125 de-energizes all relays in readiness for a new start.

The conductors 39 and 40 exemplifying parts of other units diagrammatically include the relay 792 similar to the relay 79 of unit 1 shown in Fig. 5, and also include a relay 832 similar in position to the relay 83 of unit 1 illustrated in Fig. 5.

In the several views where the relays are not shown adjacent to the contacts which they operate, the relays are diagrammatically shown in full lines as part of the wiring diagram, and repeated in dotted lines adjacent to the contacts which they operate. As an instance, in the upper left corner of Fig. 3, the relay 72 is shown in full lines as part of the wiring diagram and again illustrated in dotted lines adjacent to the contacts 65, 75 and 76.

It is obvious that various changes and modifications may be made in the details of construction without departing from the general spirit of the invention as set forth in the appended claims.

I claim:

1. A game comprising a target including a plurality of missile interceptors, each adapted to retain only momentarily a missile intercepted thereby, and a plurality of electrically operated signalling devices, each connected in an energizing circuit including a normally open switch and adapted to be completed by closing said switch, all but one of said energizing circuits including an additional normally open switch connected in a parallel branch circuit so that the energizing circuit can be completed by closing either switch, each of a number of said interceptors equal to the total number of normally open switches being provided with a normally open switch adapted to be closed momentarily

by a missile intercepted by the interceptor, each switch being connected in a circuit containing a relay means for closing a corresponding one of the switches in the energizing circuits and for completing a hold-in circuit which maintains energization of the relay means when the interceptor switch opens, each of the remaining interceptors being provided with a normally closed switch adapted to be opened momentarily by an intercepted missile, the last mentioned switches being connected in a series circuit forming a part of each of the interceptor circuits associated with one of the energizing circuits which includes a plurality of switches.

2. A game comprising a target including a plurality of missile interceptors, each adapted to retain only momentarily a missile intercepted thereby, and a plurality of electrically operated signalling devices, each connected in an energizing circuit including a normally open switch and adapted to be completed by closing said switch, one of said energizing circuits including an additional normally open switch connected in a parallel branch circuit so that the energizing circuit can be completed by closing either switch, each of a number of said interceptors equal to the total number of normally open switches being provided with a normally open switch adapted to be closed momentarily by a missile intercepted by the interceptor, each switch being connected in a circuit containing a relay means for closing a corresponding one of the switches in the energizing circuits and for completing a hold-in circuit which maintains energization of the relay means when the interceptor switch opens, each of the remaining interceptors being provided with a normally closed switch adapted to be opened momentarily by an intercepted missile, the last mentioned switches being connected in a series circuit forming a part of each of the interceptor circuits associated with the energizing circuit which includes a plurality of switches.

THEODORE B. STILLMAN.
